UNITED STATES PATENT OFFICE.

HIRAM J. HALLE, OF NEW YORK, N. Y., ASSIGNOR TO UNIVERSAL OIL PRODUCTS COMPANY, OF CHICAGO, ILLINOIS, A CORPORATION OF SOUTH DAKOTA.

REFINING HYDROCARBON OILS.

No Drawing. Application filed May 12, 1920, Serial No. 380,762. Renewed February 12, 1927.

My invention relates to a process of refining hydrocarbon oils for the production of marketable gasoline and hydrocarbon sulfonic acids.

5 Among the salient objects of my invention are to provide a process for the production of water white gasoline or light oils; to provide a process for the production of sulfonic acids of the series of hydrocarbons in 10 cracked oils, straight run oils from crude petroleum and thermal decomposition of coal, oil shales and lignites.

The process consists essentially of distilling the hydrocarbon oil through a column 15 of hot sulfuric acid of varying strengths (depending upon the type of hydrocarbon oil to be treated) while the hydrocarbon material is in vapor form.

A typical method of operation is to charge 20 the still with the hydrocarbon oil to be treated, the vapor outlet of the still passing to the bottom of the column of sulfuric acid which is maintained at a slightly higher temperature at times than the vapor coming 25 off the still. The sulfuric acid reacts with part of the hydrocarbon forming sulfonic acids of latter, while the oil vapors pass on through water and caustic soda for neutralization, yielding marketable gasoline.

30 A typical hydrocarbon oil such as a California cracked oil will illustrate my process, as to products, yields and losses.

I have successfully treated California oil in the manner hereinbefore mentioned with 35 sulphuric acid with concentrations of 20, 40, 55, 70, and 95%. With a concentration of 20% a charge of 400 cc. was distilled and yielded a gasoline percent of 52.1 of a Baumé gravity of 61.1. A similar quantity 40 of oil when distilled with a 40% solution of sulphuric acid yielded 51.2 gasoline with a Baumé gravity of 61.8 with a 55% solution a gasoline yield of approximately 50% was obtainable of a Baumé gravity of 60.6. 45 Greater quantities of sulphuric acid did not produce such high yields of gasoline and for instance, we found that with a 70% solution a gasoline percentage of 41.0 could be obtained with a gravity of 64.5.

50 The sulfuric acid sludges varied in color from light reddish to deep black as a function of the concentration of the acid used. The percentage and type of sulfonic acids varied also as a function of the acid con-

centration. The concentrated sulfuric acid 55 produced a deep black tar which upon cooling was highly viscous and asphaltic in character, showing a highly polymerizing effect upon the hydrocarbons, producing sulfonic acids of high molecular weight whereas the 60 less concentrated acid produced relatively simple molecular weight sulfonic acids of part of the hydrocarbons of the starting hydrocarbons.

Another set of tests were carried out using 65 hydrochloric acid instead of sulfuric acid, in a similar manner. The products formed were water white gasoline from the reaction (after neutralizing the oil layer) and chlorides of hydrocarbons in the hydro- 70 chloric acid "sludge" which was of a cherry red color at the end of the tests, depending upon the concentration of acid used. The water from the acid distilling over with the hydrocarbon vapors from the acid converter 75 was of a yellow to orange color. The chlorides as well as the sulfonic acids hydrocarbons can be readily converted into alcohols and acetates by well known organic reaction.

80 I claim as my invention:

1. A refining process consisting in passing oil vapors through a column of heated sulphuric acid maintained at a temperature at least equal to the temperature of the oil 85 vapors, said acid being in excess of concentration of 20% and not exceeding 55%, and in subjecting the vapors of said acid treatment to a neutralizing treatment to produce gasoline.

90 2. A process for refining hydrocarbons which comprises introducing hydrocarbon oil to a still, in subjecting oil in the still to a temperature sufficient to vaporize substantial portions thereof, and passing vapors 95 thus formed through a column of sulphuric acid in excess of concentration of 20% and not exceeding 55% and in subjecting the vapors of said acid treatment to a neutralizing treatment to produce gasoline.

100 3. The step in a process for refining hydrocarbons which comprises passing the hydrocarbons being treated while in vaporous form through a sulphuric acid solution in excess of concentration of 20% and not 105 exceeding 55%.
